R. H. COLLINGHAM,
GOVERNOR FOR PRIME MOVERS,
APPLICATION FILED DEC. 6, 1915.

1,262,454.

Patented Apr. 9, 1918.

Inventor:
Robert Hugh Collingham,

His Attorney.

UNITED STATES PATENT OFFICE.

ROBERT HUGH COLLINGHAM, OF RUGBY, ENGLAND, ASSIGNOR TO GENERAL ELECTRIC COMPANY, A CORPORATION OF NEW YORK.

GOVERNOR FOR PRIME MOVERS.

1,262,454.

Specification of Letters Patent.

Patented Apr. 9, 1918.

Application filed December 6, 1915. Serial No. 65,395.

To all whom it may concern:

Be it known that I, ROBERT HUGH COLLINGHAM, a subject of the King of Great Britain, residing at Rugby, England, have 5 invented certain new and useful Improvements in Governors for Prime Movers, of which the following is a specification.

This invention relates to governors for controlling the supply of motive fluid to 10 prime movers and more particularly to governors of the type in which the mechanism for controlling the inlet valve or valves is operated by means of a spring loaded piston actuated by fluid pressure generated 15 by means of an impeller driven by the prime mover, or at a speed proportional to that of the prime mover.

The object of this invention is to provide an improved governor of this type.

20 In the accompanying drawings, Figure 1 is a sectional elevation of one form of my invention; Fig. 2 is a similar view of a modification; and Fig. 3 shows the governor of Fig. 2 applied to an elastic fluid turbine.

25 In the modification illustrated in Fig. 1, I provide a substantially cylindrical casing 3 having a rod 4 passing down through its center. The rod is surrounded for a portion of its length by a loose sleeve 5 which 30 is driven from the prime mover in any convenient manner, as for example, as illustrated by a worm 6 and worm wheel 7. The lower end of the sleeve extends into a closed chamber 8 formed in the casing and

35 has a number of vanes 9 secured to it which operate in a suitable fluid, preferably mercury, contained in the chamber 8. The vanes are situated in a cylinder 10 provided with a sliding piston 11 which is rigidly se- 40 cured to the lower end of the central rod 4. The cylinder is submerged in the fluid which has free access to the upper edges of the vanes on the sleeve through ports 12. The space below the piston 11 is connected

45 with that above it by passages 13. The upper end of the central rod 4 is connected to a valve operating mechanism as will be explained more fully hereinafter in connection with Fig. 3, and is provided with a collar 50 14, and between this collar and the upper end of the casing 3 the governor spring 15 is located. If desired, the collar may be made adjustable so as to adjust the pressure of the spring.

55 The operation of this device is as fol-

lows: The sleeve 5 is driven by means of the worm 6 and worm wheel 7 at a speed proportional to that of the prime mover, thereby driving the vanes 9 and causing them to force the fluid against the piston 11. The 60 pressure thus created acts on the upper side of the piston 11 and causes it to descend in the cylinder 10 carrying with it the central rod and causing a movement of the valve operating mechanism to reduce the supply 65 of fluid to the prime mover. The normal position of the piston depends on the pressure created by the vanes when the prime mover is running normally, and any variation from this is followed by a raising or 70 lowering of the piston and a corresponding movement of the valve operating mechanism. The casing may be provided with a water jacket if it is considered advisable to dissipate the heat generated in the gov- 75 ernor.

The modification illustrated in Fig. 2 is quite similar to that illustrated in Fig. 1, and I have accordingly applied the same reference numerals to corresponding parts. 80 In this case the worm 6 besides being utilized to drive the sleeve 5 also drives through the worm wheel 17, an oil pump 18 which may deliver oil to an oil relay or fluid motor controlling the valve mechanism of 85 the prime mover. The structural details of this oil pump are not shown since they form no part of the present invention. It may be of any suitable type. In this arrangement the piston 11 is fixed and the rod 90 4 carries the cylinder 10 which is arranged to slide on the piston and is provided with a flange 19 at its upper end against which the compression spring 15 bears. In this respect it is the reverse of the arrangement 95 shown in Fig. 1. It will be noted that the arrangement of Fig. 2 gives a more compact structure and one in which the governor spring 10 is entirely inclosed.

The operation of this modification is similar to that of the form shown in Fig. 1. The rotation of the impeller 9 in the fluid causes a pressure to be generated in the chamber 8. This pressure acts on the bottom of the cylinder 10 causing it to descend 100 against the action of the spring 15, thereby effecting a movement of the rod 4 and through it of the governing mechanism of the prime mover.

In Fig. 3 I have shown, by way of exam- 110

ple, the governing mechanism of Fig. 2 applied to an elastic fluid turbine. 25 indicates a turbine having a valve mechanism 26 which is operated by the rod 27 connected with the power piston of a fluid motor 28. 29 indicates the pilot valve of the fluid motor having its stem 30 connected with a floating lever 31. One end of the floating lever is connected by link 32 and 10 lever 33 to rod 27, and the other end is connected by link 34 and lever 35 to the rod 4. This forms an ordinary and well known type of fluid motor control including a follow-up device for a valve mechanism. The 15 operation is obvious and is believed to need no explanation.

With governing mechanism of the above type I find that by using a relatively heavy fluid, as mercury, I can obtain a very large 20 operating force even with a low rate of revolution of the impeller.

In both the arrangements shown it will be noted that there are no external joints which are exposed to high pressure fluid and 25 hence all chance of leakage and loss of fluid from the governor is obviated.

In accordance with the provisions of the patent statutes, I have described the principle of operation of my invention, together 30 with the apparatus which I now consider to represent the best embodiment thereof; but I desire to have it understood that the apparatus shown is only illustrative, and that the invention can be carried out by 35 other means.

What I claim as new and desire to secure by Letters Patent of the United States, is,—

1. The combination with a prime mover having a valve mechanism for controlling 40 the admission of actuating fluid thereto, of a governor for actuating the valve mechanism comprising a casing, an operating fluid therein, a member fixed in the casing in spaced relation to the inner wall thereof, an 45 impeller in said fixed member, a rotating sleeve on which the impeller is fastened, said

fixed member having an opening through which fluid is fed to the impeller, a movable member which slides on the fixed member and against which fluid discharged from 50 the impeller acts, a rod which extends through said sleeve and connects the movable member to the valve mechanism, and a governor spring which opposes the movement of the movable member. 55

2. In a governor, the combination of a casing, a fixed piston therein, a cylinder which slides on the piston, said cylinder being closed at one end and having a flange, a spring surrounding the cylinder and bearing against such flange, an impeller located within the cylinder between the closed end and the fixed piston, a fluid in the casing upon which the impeller acts to create a pressure to move the cylinder, means for 60 transmitting motion to the impeller, and connecting means adapted to control a valve mechanism fixed to the cylinder. 65

3. The combination with a prime mover having a valve mechanism for controlling 70 the admission of actuating fluid thereto, of a governor for actuating the valve mechanism comprising a casing, a piston fixed therein, a cylinder which slides on the piston, said cylinder having a closed end, an 75 impeller in the cylinder adjacent the closed end thereof, a fluid in the casing upon which the impeller acts to create a pressure to move the cylinder, a rod which extends through the casing and connects the cylinder to the valve mechanism, a sleeve surrounding the rod and connected to the impeller for driving it, and a governor spring which opposes the movement of said cylinder. 80

In witness whereof, I have hereunto set 85 my hand this eighteenth day of November, 1915.

ROBERT HUGH COLLINGHAM.
